UNITED STATES PATENT OFFICE.

ALFRED M. NYGREN, OF FREEPORT, NEW YORK.

HIGH-PRESSURE-STEAM SYSTEM.

Application filed March 17, 1925. Serial No. 16,211.

To all whom it may concern:

Be it known that I, ALFRED M. NYGREN, a citizen of the United States, residing at 81 South Ocean Avenue, Freeport, L. I., in the county of Nassau, State of New York, have invented, certain new and useful Improvements in High-Pressure-Steam Systems; and I do hereby declare the following to be a full, clear, and exact description of the invention, such as will enable others skilled in the art to which it appertains to make and use the same.

The present invention relates to the art of high pressure steam heating, and aims particularly to reduce the wear on the valves and valve seats of the traps with which steam heated fixtures are ordinarily equipped.

My invention comprises a new grouping of old and standard apparatus, together with a new method of operation whereby a new result is attained.

My improved system has been devised with particular reference to the needs of hotels, hospitals, and other institutions where the maintenance of high pressure steam traps has proved troublesome and expensive. However, my invention is capable of a wide variety of uses in increasing the reliability and decreasing the maintenance cost in a great variety of steam heating systems having piped returns and operating at so-called "high pressures". By "high pressure" steam, as that expression is used in this application, I mean steam having a pressure upwardly of about 20 lbs. per square inch, in contradistinction to "low pressure" steam heating, where the pressure is ordinarily below about 5 lbs. per square inch.

The objects and advantages of the present invention will become clear from the following detailed description taken in conjunction with the accompanying drawings wherein.

Fig. 1 is a diagrammatic representation of a row of hotel kitchen fixtures operating in conformity with my present process;

Fig. 2 is a diagrammatic illustration of a modification of the invention.

It is common practice in hotel kitchens to heat soup kettles, vegetable boilers, coffee urns, and the like, with live steam at a pressure of about 40 lbs. per square inch. In order to provide for the escape of condensed

water and to permit the entrance and exit of air, such cooking devices must be provided with a trap out of which the condensed water may escape and through which air may enter when the steam supply is cut off. With pressures as high as 40 lbs. per square inch the valve in the trap must be closely adjusted and must have a small exit orifice. This causes a very high velocity for the water, air or steam, or a mixture of the three, and a resultant rapid wear of the valve and its seat. The progressive change in the exit orifice under the eroding action of these fluids makes it necessary to frequently adjust the setting of each trap, a practice that is not only expensive, but also is a source of great annoyance in a hotel kitchen. The valve seats are in themselves expensive, and the need for frequent replacement is likely to interrupt kitchen service at an inopportune time.

According to the present invention the pressure of the live steam used for heating is in large part counterbalanced by air pressure in the return pipe with a difference of say 5 lbs. per square inch between the two. As a result, the pressure drop at the fixture trap is so small that the valve of the trap need not be closely adjusted to its seat, and the velocity of the passing water, air or steam will not be high enough to seriously erode the metal of the valve or valve seat.

In the preferred embodiment of my invention automatic means are provided for maintaining a pressure of air in the return pipe so that its pressure will be below that of the live steam by a relatively fixed amount, say 5 lbs. per square inch, irrespective of any variation in the steam pressure incident to normal operation.

For purposes of illustration, I will describe my invention as applied to a group of kitchen fixtures, such as soup kettles, arbitrarily selecting a 40 lbs. steam pressure as representing a normal and typical value and arbitrarily selecting 5 lbs. pressure per square inch as the desired difference in pressure between the live steam and the back pressure of the return or drip pipe. It will be understood that much higher pressures may be dealt with and that the invention is not only useful in hotel kitchens, but can be applied to the sterilizers of hospitals, and to a great variety of equipment where chemi-

cal or physical changes are being wrought through the application of heat from steam.

In Fig. 1 high pressure steam fixtures, such as the soup kettles 1, 2, 3, 4 and 5 are supplied with live steam at 40 lbs. pressure from a main 6. Each fixture is equipped with a control valve 7 to admit or exclude steam from main 6. Each fixture is also equipped with a trap or drip valve 8 of a thermostatic variety to permit escape of air and water, but to retard as far as is feasible the escape of live steam. Each of these traps 8 discharges into a drip pipe or return line 9. The extreme outer end of steam main 6 may likewise be provided with a trap 10 discharging into return line 9 which in turn is connected with return line 11.

Steam for heating the fixtures above described may be obtained from a boiler header at 100 lbs. pressure through main 12 which is equipped with a hand valve 13. Between valve 13 and main 6 is an automatic reducing valve 14 of known construction, preferably of the spring pressed diaphragm type with an air pipe 15 connecting drip pipe 11 with the air space above the diaphragm 16 of the valve, there being a steam connection 17 from pipe 6 to the opposing side of the diaphragm. This diaphragm pressure-reducing valve is preferably set to maintain a steam pressure in main 6 about 5 lbs. above that of the air in the return line 11.

Under some circumstances it is advisable to equip the out-going stretch of pipe 6 with a trap 18 and a return drip line 19, as shown in the drawing.

Air at an appropriate pressure may be obtained in many ways, but according to the drawing, is obtained from an air compressor 20 driven by an electric motor 21 and equipped in known manner with a pressure regulator to shut off at 35 lbs. pressure. The air is delivered from the compressor through a pipe 22 into the upper side of a high pressure water tank 23. Drip pipes 11 and 19 also connect with the upper side of that tank through an intake pipe 24. The tank is also equipped with an automatic air relief valve 25, and a valve controlled by-pass 26, both communicating with an air relief line 27 which discharges into the atmosphere.

The high water line in tank 23 may be as indicated in the drawing. The level of the water may be float controlled in usual manner and tank 23 is equipped with a water discharge pipe 28 through which hot water accumulating in the tank from the steam drippings may be fed to the feed water heater of the boiler plant, or may be delivered to a storage tank, open to the atmosphere and suitably elevated, or may be taken off through a spigot, or through a bucket trap of usual construction. In as-

much as only water is to be handled through pipe 28, the task of drawing it off, even at 35 lbs. pressure is not a serious one.

With apparatus of standard construction arranged and connected as above described, the operation of the system is essentially as follows:

With valve 13 closed and with no steam in the kitchen fixtures, air compressor 20 will deliver air through pipe 22, tank 23, drip pipes 11 and 19, and the pipes connected therewith, into the steam space of the kitchen fixtures until there is attained an air pressure therein of approximately 35 lbs. per square inch. Valve 14 under these conditions will be wide open and ready to pass steam to the kitchen fixtures. Valve 13 can then be opened to admit live steam into pipe 6 by way of the pressure reducing valve 14. This steam on entering the kitchen fixtures will force out the air and raise the temperature of the fixtures. Such water of condensation as may form will pass out with the air, or subsequently thereto, but the exit of air and of water will not occur until the pressure of live steam in the fixtures is somewhat higher than 35 lbs. per square inch. The steam pressure cannot be much higher than 35 lbs. because of the automatic throttling of the air-balanced reducing valve 14. An excess of 5 lbs. in steam pressure over air pressure will be sufficient to readily clear the kitchen fixtures of air and water without violence to the traps or exit valves. The water so delivered through the traps 8 will pass down through return lines 9 and 11, into tank 23, and from there can be drawn off, either automatically or by hand, through pipe 28. If desired, the steam pressure may be built up prior to or simultaneously with the building up of air pressure.

When the system is in normal operation, the air pressure is automatically held at approximately 35 lbs. through automatic starting and stopping of condenser 20, safeguarded by the automatic air relief valve 25. The pressure reducing valve 14 will serve to keep the steam pressure at about 40 lbs. regardless of wide variations in the boiler pressure in pipe 12. Any change in air pressure will be accompanied by a corresponding change in steam pressure even to the extent of entirely cutting off the steam at valve 14 at failure of the air.

As above explained, the automatic return traps 8 and 18 need not be closely adjusted, and are not subjected to the wear of fluids at high velocity, and in materials and construction, and cost of maintenance, are not essentially different from the low pressure traps so very commonly used on the returns of radiators utilized for domestic heating.

In the system above described, the air pressure is maintained substantially con-

stant at say 35 lbs. and the steam from a boiler at much higher pressure, say 100 lbs. is automatically reduced to a pressure not exceeding that of the air by more than about 5 lbs. In Fig. 2, on the contrary, the kitchen fixtures, or that class of equipment of which kitchen fixtures are representative, receive steam directly from the boiler at whatever the boiler pressure may be, and the air pressure is automatically regulated so that it will at all times stay at about 5 lbs. below that of the steam.

In Fig. 2, the fixtures 29, 30, 31 and 32 are each provided with a hand valve 33 and receive live steam through mains 34 and 34', which communicate through a hand valve 35 with the steam supply main 34" wherein the pressure is that desired for the fixtures, it being understood that the boiler pressure will not be unsuited to the mechanical strength of the fixtures. A thermostatic trap 36 drains pipe 34 into drip line 36', and similar automatic traps 37 and 38 drain the fixtures into the return pipes 39 and 40 which empty into tank 41. From tank 41 the water can be withdrawn by hand through spigot 42, or can be discharged by way of pipe 43 into a feed water heater, a storage tank, a bucket trap, or the like, means being used for effecting the discharging automatically if desired as will be readily understood.

Air for use in counter-balancing the steam is supplied through pipe 44 at a pressure comparable to the maximum steam pressure to be anticipated in pipe 34". In other words, the air pressure at 44 is substantially above that desired in the return lines. Interposed in pipe 44 is a pressure reducing valve 45, like that heretofore described, having a steam chamber below its diaphragm 46 in communication through pipe 47 with steam main 34' and having an air or water chamber above that diaphragm and communicating through pipe 48 with drip line 36'. It is the function of this device to automatically admit air to the return lines when the pressure difference between the steam and the return lines exceeds a certain desired value, say 5 lbs. per square inch. In other words, this device will increase the air pressure as the steam pressure goes up, and is calibrated to keep the air pressure about 5 lbs. below the steam pressure. To take care of the conditions resulting from a falling steam pressure, there is provided a second pressure reducing valve 49 interposed in an air discharge line 50 which communicates at one end with drip line 40, and at its other end discharges into the atmosphere. The chamber below its spring-balanced diaphragm 51 communicates through pipe 52 with air pipe 50, and the chamber above its diaphragm communicates through pipe 53 with steam line 34. As thus arranged, this

device acts to automatically discharge air from the return or drip line when the pressure difference between the steam and the return line is less than a certain desired value, say 5 lbs. per square inch. ⁷⁰

By the grouping of standard apparatus in the manner above described, steam at boiler pressure may be used to heat the fixtures, and the counter-balancing air pressure will fluctuate up or down in such a way ⁷⁵ as to keep the air pressure in the return lines just enough lower than the active steam pressure in the fixtures to permit ready discharge of air or water from the fixtures without excessive velocity or wear at the automatic ⁸⁰ drip valves or traps of the fixtures.

As above indicated, I have used the term "fixtures" herein as generic to kitchen kettles, hospital sterilizers, heating coils of evaporators, high pressure steam mains, ⁸⁵ and other like apparatus and equipment, and, in general, steam consuming apparatus operable on high pressure steam, in contradistinction to the low pressure heaters suited to exposed heating in domestic installations. ⁹⁰

I am aware that many changes can be made in details of the several elements and in the grouping of those elements and in their mode of operation, without departing from the spirit of my invention as defined ⁹⁵ by the appended claims.

I claim:

1. The combination of a heating fixture having a trap with a relatively large orifice, means for supplying high pressure steam to said fixture, and means for counterbalancing said steam at said trap with air at a slightly lower pressure, substantially as described. ¹⁰⁰

2. The combination of a heating fixture having a trap with a relatively large orifice, a drip pipe leading from said trap, a water tank into which said pipe discharges, means for supplying steam to said fixture, and means for maintaining an air pressure in said tank and drip pipe slightly below the steam pressure at said trap. ¹⁰⁵ ¹¹⁰

3. The combination of a heating fixture having a thermostatically trapped outlet with a relatively large orifice, a drip pipe leading therefrom, a water tank into which said drip pipe discharges, means for automatically withdrawing water from said tank, means for supplying high pressure steam to said heating fixture, and means for maintaining an air pressure in said drip pipe approximately 5 lbs. below the steam pressure in said fixture, substantially as described. ¹¹⁵

4. The combination of a heating fixture having a discharge trap with a relatively large orifice, a drip pipe leading therefrom, means for supplying high pressure steam to said heating fixture at a pressure which is substantially constant, and means for supplying air to said drip pipe at a pressure ¹²⁵ ¹³⁰

which is substantially constant and which is about 5 lbs. below the pressure of the steam in the heating fixture.

5. The combination of a heating fixture having a discharge trap, a drip pipe leading therefrom, means for delivering compressed air to said drip pipe at substantially constant pressure, means for delivering high pressure steam to said fixture, and automatic means for regulating the steam in said fixture to a pressure slightly higher than the pressure of the air in said drip pipe.

6. In a system of the character described, the combination of a heating fixture having a thermostatic trap with a relatively large discharge orifice, a drip pipe connected therewith, a water tank into which said drip pipe may discharge, an air compressor automatically regulated to normally deliver air to said tank and drip pipe at a constant pressure, means for delivering high pressure steam to said fixture, and means for automatically regulating the pressure of the steam in the fixture to a value about 5 lbs. above the pressure of air in said tank and drip pipe.

7. The method of reducing wear in the trap of a fixture heated by high pressure steam which consists in counter-balancing the steam on one side of said trap with air on the other side of said trap, said air being at a pressure slightly below that of the steam, substantially as described.

8. The method of reducing the wear and maintenance cost on the drip trap of a fixture heated by high pressure steam which consists in setting the trap to a relatively wide orifice and partly counter-balancing the

steam on one side of said trap with air on the other side thereof, the respective pressures of steam and air being maintained relatively close to one another, substantially as described.

9. The method of reducing the wear and maintenance cost on the trap of a fixture heated with steam at high pressure which consists in maintaining a substantially constant air pressure on the exit side of said trap and automatically correlating the pressure of steam on the other side of said trap to a value about 5 lbs. higher.

10. The method of operating a high pressure steam heated fixture having a steam trap, and a drip pipe connected therewith, which consists in adjusting said trap to a relatively large discharge orifice, maintaining a substantially constant air pressure in said drip pipe, and automatically regulating the supply of steam to said fixture so that the steam pressure on one side of said trap will be about 5 lbs. greater than the air pressure on the other side of said trap.

11. The method of operating at high steam pressure a heating fixture having a steam trap communicating with a water tank through a drip pipe, which consists in maintaining a substantially constant air pressure in said tank and pipe, supplying high pressure steam to said fixture, and automatically regulating said supply of steam to said fixture at a pressure near enough to the pressure of the air in said drip pipe to permit a relatively wide opening of said trap, substantially as described.

In testimony whereof I affix my signature.
ALFRED M. NYGREN.
